UNITED STATES PATENT OFFICE.

JEFFREY T. FERRES AND WALTER H. FAIRCHILD, OF ANDERSON, INDIANA, ASSIGNEES OF ONE-HALF TO J. W. SEFTON MANUFACTURING COMPANY, OF ANDERSON, INDIANA, A CORPORATION OF INDIANA.

PAPER BOX.

No. 901,286.

Specification of Letters Patent. Patented Oct. 13, 1908.

Application filed August 9, 1906. Serial No. 339,889.

To all whom it may concern:

Be it known that we, JEFFREY T. FERRES and WALTER H. FAIRCHILD, citizens of the United States, residing at Anderson, Madison county, Indiana, have invented certain new and useful Improvements in Paper Boxes, of which the following is a specification.

Our invention relates to paper boxes preferably those which are made from corrugated paper board and the object thereof is to provide simple and efficient means whereby the box after being folded in shape and sealed may be readily opened for any purpose such as for inspection or for obtaining access to and removing the contents. These opening means are such as to permit of the opening of the box in convenient manner and without liability of any damage or injury whatsoever to the contents and moreover such means, in their preferred form as herein illustrated, are such as to leave the top of the box intact after the box is opened and to permit the same to be used as a lid, which in the present instance, is hinged to the body of the box.

Our invention may be embodied in boxes of different character and construction but for the sake of convenience and for definite description we will describe the same as embodied in a folding box made of double-faced corrugated paper board which is formed in two parts or shells, an inner shell and an outer shell, although as will be evident the employment of the inner shell is not essential or required except for a heavy box. Our invention is therefore not restricted except as specifically claimed in some of the claims, to the special features of construction of the particular box herein illustrated and about to be described.

In the drawings Figure 1 is a perspective of the blank of the outer shell of the box illustrating the tearing tape or string in place thereon; Fig. 2 a perspective of the blank of the inner shell; Fig. 3 a perspective of the box folded with the exception of the top extensions which, when folded down, form the lid of the box; Fig. 4 a transverse section on the line 4—4 of Fig. 3; Fig. 5 a perspective of the box complete in assembled form and showing the same partially opened; Fig. 6 a cross section of the box after being opened by said opening means and illustrating the

lid in open condition; and Fig. 7 a section on 55 the line 7—7 of Fig. 5.

Referring to the present embodiment of my invention as illustrated in the drawings, the particular box herein illustrated is composed of two main parts or shells, an outer 60 shell or box and an inner shell or box nested therewithin, the blanks of which shells are illustrated in Figs. 1 and 2 respectively.

Referring to the outer shell, whose blank is illustrated in Fig. 1 the same comprises 65 the four side walls 1, 2, 3 and 4 of which the last three are in the present instance hinged together by their own material while the first one is hinged to side wall 2 in suitable manner as by means of the hinge-tape 5. The 70 side walls 1 and 4 are arranged to be hinged together by means of the hinge-tape 6. The side walls are each provided with extensions 1^a, 2^a, 3^a and 4^a at their opposite ends to form the top and bottom respectively for the box 75 when the same are folded over upon each other in the manner hereinafter described.

Referring next to the inner shell, as shown in Fig. 2, the same comprises four side walls 7, 8, 9 and 10 of which the side walls 7 and 8 80 are hinged by their own material and likewise the walls 9 and 10, the pairs of walls being in the present instance hinged together on the hinge-line between the walls 8 and 9 in suitable manner as by means of a hinge-tape 11, the two walls 7 and 10 being hinged by a similar hinge-tape 12. The walls of the inner shell are of a size a little smaller than the sides of the outer shell with the result that the inner shell is arranged to be inserted 85 or nested within the outer shell, as indicated in Figs. 3, 4 and 6.

In practice, in assembling the box the bottom is formed and sealed by folding the lower end extensions 1^a, 2^a, 3^a and 4^a inwardly, in pairs, the two lower extensions 1^a and 3^a being first folded inwardly and then the two other corresponding extensions 2^a and 4^a, or vice versa. The two pairs of these extensions, thus forming the bottom of 100 the box, are firmly secured together in suitable manner as by gluing them together, the glue being applied between the two pairs of said extensions. The inner shell is now inserted in place, Figs. 3 and 4, and the goods 105 to be contained within the box are introduced therein, after which the top extensions are folded over in a manner similar to

to the lower extensions as already described and the pairs of extensions are likewise glued or otherwise secured together with the result that the box is firmly and tightly glued and sealed at all points including both ends. The box will now appear as shown in Fig. 5 with the exception that the box is not partially torn as illustrated therein.

In a box which is constructed and is sealed as hereinbefore described it is difficult to open the box without the expenditure of considerable time and labor and without danger of damaging the goods therewith especially if the box is opened by cutting the same.

15 It is the object of our invention to provide simple and efficient means for opening a paper box of the character hereinbefore described or boxes of similar character and as herein shown we obtain this object by providing a tape or string which is so connected or associated with the box that the action of pulling upon one end thereof tears or rather severs the box, preferably through a plurality (in the present instance three) 20 of the side walls thereof, leaving the top of the box intact and capable of being used as a lid or the like to close the box after the same has been once opened either by the consumer or jobber or by the employees of 25 a railway for instance for inspection purposes.

As herein shown the tape or string 13 is secured in suitable manner upon the inner side or surface of the three side walls 2, 3 35 and 4 which are selected as the ones to be severed in the operation of opening the box. This tape may be secured at any number of points along its length sufficient to hold the same in proper relationship and coöperation with such side walls but by preference and as shown in the drawings we secure the same by gluing it directly to the inner surface of said three side walls 2, 3 and 4. This tape is secured to the side walls a short distance 40 from the upper edge or top thereof but in the present instance, for a purpose hereinafter made apparent, the extreme ends of the tape are curved upwardly so as to emerge at the upper corners of the side walls 2 and 45 4. Moreover one or both ends of the tape may be caused to extend slightly extraneous of the box so that the same may be grasped or caught by the operator.

50 In practice, the operator takes hold of the end of the tape and pulls upon the same, say 55 forwardly of the box, that is to the left in Fig. 5, with the result that the side walls of the box are severed transversely, as shown in Fig. 5 wherein the first part of the operation 60 is indicated. According to the construction illustrated in the drawings only three of the side walls are thus severed so that the top of the box with those portions of the side walls which are left attached is hinged to the 65 fourth wall 1 and consequently such top of

the box, after being opened, is capable of serving as a lid in the manner clearly indicated in Fig. 6 in which the lid is shown as thrown open. In other words, the box which was closed and sealed and unprovided with a lid or cover is thus not only opened by the severing of the side walls as described, but also provided with a lid or cover in the act of and as an incident to the opening of the box. By running the extreme ends of the tape 13 to the corners of the side walls 2 and 4 the lid is caused to open and close without difficulty or interference. Moreover, when an inner shell is employed, as in the present instance, that portion of the side walls thereof which project above the severed portion of the side walls of the outer shell constitute a flange, Fig. 6, for the lid and enable the latter to fit closely upon the box proper and to enable the same 85 to be again securely closed when it is desired to do so after the box has been once opened.

As hereinbefore stated it is preferable to so arrange the tape 13 as to cause a severing of only three of the four side walls of the 90 box so that the top may be left intact and hinged upon such fourth side wall. It will be obvious, however, that the tape 13 may be extended across said fourth side wall 1 so that the box may be severed as to all four of 95 its sides and the top be bodily removed. It will also be understood that in this event the tapes 5 and 6 would be transversely slotted or cut across so as to permit of the severing operation transversely thereof. Furthermore, it will be understood that any suitable means may be provided for securing the tape 13 in its proper place on the inner surface of the side walls of the box but it is at present preferred to secure the same by gluing, it being desirable that the tape should have intimate contact and anchorage as to its entire length to facilitate its severing action. This tape could be secured at the 105 corners between the side walls 2 and 3 and 3 and 4 but the securing of the tape along its entire length is preferred as hereinbefore stated, more particularly for the reason that the tensile strain on the string is thereby reduced and the severing or cutting action of 110 the tape increased. In practice and as herein shown, where we employ the double faced corrugated paper board for the outer shell, for instance, the corrugations extend or run 115 transversely of the shell or body of the box and the tape extends or runs parallel with said corrugations, with the result that when such tape is pulled the side walls forming the body of the box are severed along the line of the corrugations, the severing action 120 being more easily and readily done when this relative arrangement of the corrugations and tape obtains.

125 Although we have herein referred to the severing device as a string or tape, because such 130

is the device employed by us, yet it will be understood that any equivalent device for accomplishing the same result is within the scope of our invention and claims, for instance, a small wire could be substituted for the string or tape. It will also be understood that where the length of the box exceeds the width and it is desirable that the top and bottom should be composed of two 10 thicknesses of material over the entire surface, the flaps 1^a on piece 1 Fig. 1 may be made longer so as to meet the flaps 3^a and thus cover the entire top and bottom with two thicknesses of material, not leaving the 15 space between the flaps as shown in Fig. 5, or if the tape 18 is attached to the sides of 1, 2 and 3, and the flaps 1^a, 2^a and 3^a made long enough so flaps 1^a and 3^a will meet, the flaps 4^a can be shortened to meet 2^a.

20 We claim:

1. In a paper box, the combination, with the two ply side walls and ends thereof, of a tape or string positioned at the inner surface of a plurality of the outer set of side walls whereby upon pulling the tape such walls are severed and the box thereby opened.

2. In a paper box, the combination, with the two ply side walls and ends thereof, of a tape or string secured to the inner surface of a plurality of the outer set of side walls and having an end extending extraneous of the box, whereby upon pulling the tape such walls are severed and the box thereby opened.

3. In a paper box, the combination, with the side walls and ends thereof, of a tape or string glued along its length to the inner surface of a plurality of the side walls and having an end extending extraneous of the box, whereby upon pulling the tape such walls are severed and the box thereby opened.

4. In a paper box, the combination of the side walls and end extensions which are secured together to form the ends of the box and to seal the same, and a tape or string positioned at the inner surface of a plurality of the side walls near one end of the box and adapted to be pulled to sever such side walls whereby the box is opened and whereby said end may still serve as a 45 cover in connection with the upper portion of the box so severed.

5. In a paper box, the combination of the side walls and end extensions which are secured together to form the ends of the box and to seal the same, and a tape or string arranged on the inner surface of three of the side walls near one end thereof and adapted to be pulled to sever such side walls, whereby the box is opened and whereby said 50 end together with the upper portion of the box so severed may serve as a lid hinged on the remaining side wall of the box.

6. In a paper box, the combination of the side walls and end extensions which are secured together to form the ends of the box

and to seal the same, and a tape or string arranged on the inner surface of three of the side walls near one end thereof and adapted to be pulled to sever such side walls, whereby the box is opened and whereby said 55 end together with the upper portion of the box so severed may serve as a lid hinged on the remaining side wall of the box, the main portion of the tape being positioned at the same distance from the end of the box but 60 the ends thereof extending obliquely to the corners of those side walls in which they terminate.

7. In a paper box, the combination of an outer shell or box comprising side walls and end extensions arranged to be secured together to form sealed ends for the box, an inner shell or box composed of side walls corresponding with and fitting within the side walls of the outer shell, and a tape or string positioned at the inner surface of the outer shell near one end thereof and below the top plane of the inner shell, whereby, when the tape is pulled the outer shell is severed, that end of the shell adjacent thereto remaining intact and the inner shell forming a flange therefor.

8. In a paper box, the combination of an outer shell or box comprising four side walls, three of which are formed from a single 95 blank and the fourth of which is separate but hinged thereto, and a tape or string secured to the inner surface of said series of three side walls and having an end extending extraneous of the box at a point adjacent 100 the line of hinging of said fourth side wall whereby when the tape is pulled the body of the side walls is severed.

9. In a paper box, the combination of a shell or box comprising four side walls, end 105 extensions hinged thereto and arranged to be folded to form ends of double thickness and to be secured together, and a tape or string positioned at the inner surface of the shell or box near an end thereof whereby 110 when the string is pulled the shell is severed and the box opened, a portion of the side walls remaining attached to those extensions forming one of the ends to form a cover for the box.

10. In a paper box, the combination, with the side walls and ends thereof formed of two plies of double-faced corrugated board, of a tape or string secured to the inner facing of the outer ply of said board whereby upon pulling the tape such ply is severed and the box thereby opened.

11. In a paper box, the combination of a shell or box formed of double-faced corrugated board and consisting of four side 125 walls 1, 2, 3 and 4 having at opposite ends the pairs of extensions 1^a and 3^a and likewise the extensions 2^a and 4^a being foldable inwardly to form the ends of the shell or box, and a tape 18 secured to the inner face or surface 130

of three of the side walls and having an end extending extraneous of the box at the hinge between one of the side walls and the remaining side wall whereby when the tape is pulled said side walls are severed and the box thereby opened, one of said ends and the upper severed portion of the body of the box forming the cover.

12. In a paper box, the combination of a box proper formed of double-faced corrugated board and consisting of side walls hinged together and end extensions adapted to be secured together to form the ends of

the box, the corrugations of the board running transversely of the body of the box, and a tape secured to the inner face or surface of three of the side walls and extending parallel with said corrugations, whereby when the tape is pulled the side walls are severed along the line of the corrugations. 15
